UNITED STATES PATENT OFFICE.

CARL SCHRADER, OF HALENSEE, NEAR BERLIN, GERMANY, ASSIGNOR TO SIEMENS & HALSKE, A. G., OF BERLIN, GERMANY, A CORPORATION OF GERMANY.

COIL.

No. 926,964.

Specification of Letters Patent.

Patented July 6, 1909.

Application filed August 4, 1908. Serial No. 446,973.

To all whom it may concern:

Be it known that I, CARL SCHRADER, a subject of the German Emperor, and residing at Halensee, near Berlin, Germany, have invented certain new and useful Improvements in Coils, of which the following is a specification.

The present invention relates to coils, particularly for electrical purposes, and an important object is to provide improved electrical conductors which can readily be wound into a coil having a large cross-sectional area.

In all instances in electromagnetic apparatus for heavy currents having a plurality of turns of large cross-sectional-area, when it is a matter of importance to obtain as good utilization as possible of the space which is limited to a minimum amount, as is known great difficulties are met with in constructing and arranging such windings and their ends. This is very noticeable particularly when constructing electromagnetic apparatus for high tensions, such as transformers for example, in which case, on account of it being necessary to observe definite paths and spaces for insulation, a useless enlargement of the winding-space, which is connected with considerable use of material, and a positively injurious increase in length of the path of the lines of force are caused by the enlarged iron cores.

Now an important object of the present invention is to provide conductors for making, in a more simple manner, coils having two or more turns of large cross-sectional area, so that not only are the above mentioned defects avoided, but in addition the advantage is obtained of being able to employ such coils particularly for closed iron cores, in which case the arrangement of the windings customary heretofore is, connected with special technical difficulties.

In order that the invention may be clearly understood, reference will be made to the accompanying drawing in which one embodiment is represented by way of example, and in which:

Figure 1 is a sectional elevation of a coil according to the present invention, whereas Fig. 2 is a front elevation of part of a strip of metal prepared ready for being wound into a

coil. Fig. 3 is a front elevation of a strip comprising two complementary halves.

For making coils of two or more turns, according to the present invention suitably long strips of metal p_1 , p_2 , etc., corresponding to the number of turns necessary in each case are employed which are provided at suitable distances corresponding to the circumference of each turn with suitably shaped holes l which serve for the passage of the inner end of the coil and for insulation around the same. Such coils can be particularly conveniently wound, since at each turn the perforated places of the strip of metal is simply placed over the previously bent, insulated, inner end, and the latter is finally mechanically connected with the other end of the finished coil. Both ends are separated from one another by an insulating layer and form the connections of the coil. In coils which are made in this manner both the noxious space which is produced on account of the inside or commencing end of the coil being brought out laterally, and the enlargement of the coil or of the iron core which is to be wound which is thereby occasioned are avoided. On account of the inner end being passed through the individual turns, the coil is simultaneously prevented from flying open. The manner in which such a coil is made will be readily understood from Figs. 1 and 2; a is the outer end of the strip of metal which is provided with holes l at definite intervals corresponding to the circumference of each turn. The preliminarily bent inner or commencing end b is passed through, and insulated from the sides of the superposed holes in the winding, and after the strip has been wound up the commencing end is connected with the outer end a , a layer of insulation being placed between them.

The commencing end of the coil does not always require to be brought out in the center of the strip, as shown in Figs. 1 and 2 of the accompanying drawing, but may be passed through the same at optional places, for example at either edge also. Also under certain circumstances, for example when specially long coils have to be wound, it is preferable to subdivide the strip longitudinally, for example in such manner that as

shown in Fig. 3 the strip consists of two symmetrical halves *a* and *a'*. The holes *l* and *l'* through which the inner or commencing ends *b* and *b'* are to pass are at one edge of 5 each half strip.

What I claim as my invention and desire to secure by Letters Patent is:

1. The herein-described coil consisting of a plurality of superposed broad strips of metal 10 corresponding in breadth to the breadth of the coil and having at definite intervals holes in the same corresponding to the separate turns of the coil, through which holes the commencing end of the coil passes to the 15 outside.
2. The herein-described coil consisting of a plurality of superposed broad strips of metal corresponding in breadth to the breadth of the coil and having at definite intervals holes 20 at one edge of the same corresponding to the separate turns of the coil, through which holes the commencing end of the coil passes to the outside.
3. The herein-described coil consisting of a 25 plurality of superposed broad strips of metal divided longitudinally into symmetrical halves and having at definite intervals holes

at one edge of each half of the same corresponding to the separate turns of the coil, through which holes the commencing end of 30 the coil passes to the outside.

4. The herein-described coil consisting of one broad strip of metal corresponding in breadth to the breadth of the coil and having at definite intervals holes in the same corresponding to the separate turns of the coil, through which holes the inner or commencing end of the coil passes to the outside. 35

5. The herein-described broad strip of metal having a plurality of holes in the same, the distances between each two adjacent holes being equal to the corresponding circumference of the individual turns of a coil composed of said strip of metal, substantially as described, with reference to the 40 drawing.

In testimony whereof I have signed my name to this specification in the presence of two witnesses.

CARL SCHIRADER.
